UNITED STATES PATENT OFFICE.

SAMUEL EDWARD JENKINS, OF RICHMOND, VIRGINIA.

APPARATUS FOR HANDLING ASHES, GARBAGE, AND OTHER REFUSE.

1,143,278.

Specification of Letters Patent. Patented June 15, 1915.

Application filed February 10, 1914. Serial No. 817,951.

To all whom it may concern:

Be it known that I, SAMUEL EDWARD JENKINS, a citizen of the United States, residing at Richmond, in the county of Henrico and State of Virginia, have invented certain new and useful Improvements in Apparatus for Handling Ashes, Garbage, and other Refuse, of which the following is a specification.

10 This invention relates to certain improvements in apparatus for delivering and discharging refuse and the like; and the objects and nature of the invention will be readily understood by those skilled in the 15 art in the light of the following explanation of the accompanying drawings illustrating what I now believe to be the preferred embodiments from among other formations, arrangements and constructions within the 20 spirit and scope of the invention.

An object of the invention is to provide apparatus operative from a kitchen or other receiving station for automatically delivering ashes, garbage, etc., into elevated receptacles located adjacent to an alley, or other point, and adapted to discharge the same into ash or garbage wagons.

A further object of the invention is to provide means for conveying refuse from a 30 kitchen or other part of a building and automatically dumping the same into a storage can or other receptacle so located and arranged that the ash or garbage man can readily discharge the contents of such can into the garbage or other wagons.

A further object of the invention is to provide elevated cans or receptacles for the reception of garbage, ashes, etc., with means whereby said cans can be readily dumped to 40 discharge their contents into wagons, and with means for normally closing said cans and thereby covering the contents thereof, and with means for conveying garbage, ashes, etc., from a remote point and dumping the same into such cans, said means being operative from said remote point.

A further object of the invention is to provide improvements in and relating to apparatus for conveying refuse from a remote point and discharging the same into means for delivering the refuse to collection wagons or the like.

The invention consists in certain novel features in construction and in combinations, arrangements and constructions as

more fully and particularly set forth and specified hereinafter.

Referring to the accompanying drawings: Figure 1, is a side elevation, more or less diagrammatically illustrating apparatus 60 embodying my invention. Fig. 2, is a top plan. Fig. 3, is a vertical section on the line 3—3, Fig. 1. Fig. 4, is an elevation of a portion of the apparatus showing the support for the cans swung from normal position to carry one can to receiving position, dotted lines showing the support of the other can extended and said can in reversed or dumping position. Fig. 5, is a horizontal section in the plane of the line 5—5, Fig. 3, 70 but showing the cans in normal position by full lines, and by dotted lines in receiving and dumping positions. Fig. 6, is a vertical sectional view illustrating certain details.

Where my invention is embodied in apparatus for delivering refuse from a kitchen or other part of a building remote from an alley or other road along which the refuse collection vehicles pass, to said collection vehicles, I provide operating means in or 75 adjacent to the kitchen or other desired part of the building, supports for maintaining cans in elevated positions adjacent to the alley so that the contents of such cans can be discharged into the collection vehicles by 80 reversing or dumping the cans while carried by said supports, and means operative from the kitchen or other part of the building for receiving the refuse and for conveying the same to and automatically discharging 85 the same into any one of said cans. For instance, in the kitchen, or at any other station or location where it is desirable to have the operator stand, I provide a fixed vertical post or support 1, in the upper end of 90 which I mount a vertically disposed sheave or grooved wheel or pulley 2, rotating on a horizontal axis 3, and provided with a handle 4.

At the discharge station (at the alley or 100 adjacent to the road where the collection vehicles stop to receive the load) I provide a fixed elevated post or support 5, in the upper end of which is mounted a vertically rotatable sheave, or grooved wheel or pulley. 105

The pulleys 2 and 6, receive and carry an endless traveling connection 7, formed by a flexible wire or cable of the requisite strength having its parallel upper and lower plies extending from the refuse receiving 110

station to the refuse discharge station. This endless connection is actuated to travel in either direction by the rotation of the wheel 2, through the medium of its handle 4. This 5 endless connection actuates a car or carriage 8, on its travel back and forth between the receiving and discharge stations.

The carriage is preferably arranged below the upper and lower plies of the cable 7, 10 and travels freely with respect to the upper plies of the cable but is included in and propelled by the lower ply of the cable. For instance, I show uprights 9, pivotally coupled to and extending up from the front and 15 rear ends of the carriage and at their upper ends having wheels 9^a, traveling on the upper plies of the cable 7. I also show the upper ends of these uprights connected by brace 11, arranged below said wheels and 20 plies of the cable. The lower ply of the cable includes means for taking up the slack in the cable or for adjusting the cable. For instance, I show the lower ply of the cable including a turn buckle 10, having its end 25 loops 10^a, 10^b, secured to the cable ends so that the turnbuckle as an entirety connects said cable ends to provide the endless carriage-operating connection. The cable is secured to the carriage 8, through the medium of this turn-buckle to propel the carriage back and forth between the wheels 2, 6. For instance, the loop 10^b, of the turn-buckle is fixed to a vertical plate or ear 30 fixed to one end of the carriage and to which one upright 9, is pivoted while the other loop 10^a, is freely slidable longitudinally through the other vertical plate fixed to the opposite end of the carriage and to which the other upright 9, is hinged or pivoted, to 35 permit adjustment of the turn buckle in tightening or loosening the endless carriage propelling connection.

The carriage forms an open-top horizontally-disposed receptacle having its lower 45 discharge end normally closed by a longitudinally slidable door or bottom 12, having depending swingable hooks 13, by which the bottom is opened, as hereinafter described, to dump the contents of the carriage.

50 The carriage is preferably arranged between and travels longitudinally of a pair of parallel cable or wire lengths 14, and if so desired, is supported by said lengths 14, through the medium of small grooved wheels 55 14^a, traveling on said wire lengths and exteriorly arranged at the opposite sides of the carriage and mounted on spindles or shafts secured to the carriage.

In the particular example illustrated, the 60 wire lengths 14, form an endless connection passing around and secured to horizontally disposed sheaves 15, 16, centered and horizontally rotatable on the posts 1, 5, and arranged below the vertically disposed wheels 65 2, 6. The sheave 15, is provided with a han-

dle 15^a, by which the same can be turned in either direction to correspondingly oscillate or turn the sheave 16, through the medium of connection 14.

The posts 1, 5, are provided with arms or 70 brackets 17, rigid therewith and having horizontal cross heads extending between the two plies of the connection 14, and at their ends forming guides for connection 14, and having supporting guides 18, therefor. 75 These brackets also form bumpers or stops limiting the movements of the carriage to stop the same at the receiving station, when the carriage is moving on its return passage, and to stop the same at the discharge station 80 when the carriage is moving on its delivery trip or passage. The horizontal sheave 16, is fixed to the upper end of a sleeve 19, surrounding and mounted to rotate on the post 5. This sleeve is supported by any suitable 85 means, although in the example illustrated, the sleeve is carried by and rotates in the upper end of a head or cap 20, fixed on a supporting column 21. The post 5, extends down through said head and into said column and is fixed against rotation. The head provides a suitable supporting bearing for the sleeve such as ball bearing 22, within the head and on which the lower end of the sleeve rests. The sleeve 19, is provided with 90 a laterally projecting cross head that carries and supports the two reversible ash and garbage cans or receptacles 23.

The cross head consists of a center hub 19^a, and a pair of radiating arms or brackets 100 projecting laterally in opposite directions therefrom. Each bracket consists of a rigid member 24, fixed to the hub, and a horizontally swingable can-carrying member 25. The member 24, has a fixed depending vertical inner end portion and a fixed horizontal outer end portion. The swingable member 25, is at one end hinged to the outer or free end of the member 24, by a vertical pivot 26, while the opposite or free end of the arm or member 25, is provided with a vertical upright 27.

One of the open top cans 23, rests on the arm or member 25, and is pivotally joined thereto by loops or eyes 28, depending from the bottom of the can and embracing said arm, so that the can can swing thereon from normal upright position with its bottom resting on and approximately diametrically traversed by said arm 25, to the reversed or 120 discharging position with the can hanging or depending from the arm. The can is held in normal upright position on the swingable arm by the latch 29, arranged at the exterior of the can and detachably engaging the fixed 125 upright 27 of the arm. The swingable arm 25, is normally arranged in its inwardly swung or folded position directly over and parallel with the horizontal outer portion of the bracket member 24, and detachably 130

held in such position by the supporting rest or pillar 30, having a top depression on which the free end of the swinging member rests and by which it is detachably held 5 against swinging on the pivot 26.

The hub 19^a, rests on the top edge of the head 20, and is rotatable thereon and around the sleeve 19, but said hub is normally locked to the sleeve and against rotation independently thereof, by a suitable exposed readily accessible pivoted latch 31, and its keeper whereby the cross head and its hub can be released from the sleeve for rotation independently thereof when required.

15 The cross head is normally arranged in a transverse position with respect to the end-less connections 7, 14, and is provided with two similar cans 23, arranged the same distance from the post 5, and at opposite sides 20 thereof and tending to approximately counterbalance each other to a greater or lesser degree. The cans when thus arranged in normal upright position are out of operative, or coöperative, position with respect 25 to the carriage 8, and are also out of operative dumping position with respect to the collection wagons. It might be said that the cans are in storage position when thus held in normal position and out of receiving 30 and dumping positions.

The cross head is swung through an arc of ninety degrees to bring one can to receiving position and the other can to dumping position. This will bring the cross head to a 35 position at right angles to its normal position and one can will be thereby carried rearwardly to a position over the alley or road so that a collection wagon can be driven thereunder to receive the contents of said 40 can when reversed, while the other can will be brought forward to a position directly below the connections 14, and below the discharging position of the carriage. When a can is thus in the forward or receiving position its rim will engage the hooks 13, depending from the sliding bottom of the carriage, as said carriage approaches discharging position, and will thereby hold the bottom back as the carriage is carried forward 45 over the open top of the can, whereby the contents of the carriage will be automatically discharged into the can by the power supplied by the operator in rotating wheel 2. When the contents of the carriage have been 50 deposited in the can, the operator rotates the wheel 2, in the opposite direction and thereby returns the carriage to receiving position, and on its arrival at receiving position, the operator should slide the bottom 12, back to 55 closed position.

The operator in the kitchen or at any other point where the operating wheels 2, 15, are located, can bring either can 23, to the receiving position by turning the wheel 15, a quarter turn to the right or to the left.

Usually, one can 23, is provided to receive garbage and the other can 23 to receive ashes, and the wheel 15 can be provided with suitable indications to guide the operator in turning the wheel in the proper direction to bring either the garbage or the ash can to receiving position, as may be desired. For instance, I show one spoke of the wheel 15, provided with a vertical hole or a socket and bearing the letter A adjacent to said socket, 70 while the diametrically opposite spoke of the wheel is formed with a vertical hole or socket and is provided with a letter G adjacent said socket. An intermediate spoke of the wheel is shown formed with a 80 socket B.

The post 1, is provided with a bracket 35, fixed thereto and extending laterally therefrom and carrying a vertically movable bolt or latch 36, adapted to enter any one of said 85 sockets A, G, B, and lock the wheel against rotation. The wheel is in its normal position when the socket B, is under the bolt 36, and locked thereby, to hold the cross head and cans in normal positions. If the operator 90 then desires to bring the ash can to receiving position, the bolt is elevated from the wheel and the wheel is turned toward the left until socket A is under the bolt and the wheel has been locked thereby. When the carriage has 95 deposited its load in the ash can, the carriage is returned, and the bolt is released from wheel 15, and said wheel is turned toward the right to restore the cross head and cans to normal positions and said parts are locked 100 in normal position by the bolt. The wheel 15, is turned toward the right to bring the garbage can to receiving position and the bolt is dropped into socket G, to lock the parts until the can receives its load from the 105 carriage.

To collect the garbage, ashes etc., it is merely necessary for the collection wagon to drive up adjacent to the elevated can so that the collection man can, from his 110 wagon, reach the latch 31, and release the same from its keeper (and thereby release the cross head from the sleeve 19) and then swing the cross head from normal position to move one of the cans rearwardly for reversing over the wagon to dump the contents of the can into the wagon. When the cross head has swung from normal position, the swingable can-carrying member 25, is sprung up from the depression in rest 30 and 115 said member is then swung rearwardly to carry the can over the wagon body. The catch 29, is then released and the can allowed to drop to reversed position to dump its contents into the wagon body. The can is 120 then swung up to upright position and locked in such position by the latch 29. The arm 25 is then swung to normal position over the arm 24, and is locked in such position by the engagement of its free end in the depres- 130

4
 sion of the supporting rest 30. The cross head is then swung back to normal position and locked to the sleeve 19, by the latch 31, so as to be operatively coupled through 5 the wheel 16, and connection 14, to operating wheel 15.

Suitable mechanism is provided for covering or closing the open tops of the cans when in normal or storage position. For instance, I show a pair of fixed arms 38, projecting laterally and oppositely from the post 5, and elevated above the cans when in storage position. These arms have 10 pending free ends arranged centrally over the cans, and bell-like covers 39, are suspended from said free ends to rest on the cans when in storage position. Each cover is pivotally suspended from its center and is allowed a limited vertical movement independently of its supporting arm, so that the cans can freely move laterally from under the covers when the cross head is swung, leaving the covers suspended from the fixed 15 arms 38. When the cross head is swung back to normal position, the rims of the cans will engage the covers and in moving under the covers, will swing and elevate the covers so that when the cans come to rest at storage 20 position, the covers will rest on the rims of the cans, and each can will bear the weight 25 of its cover and will be approximately tightly closed thereby.

In the particular example illustrated, the free ends of the cover carrying arms are 30 provided with transverse pivots 40, and the covers have metal straps 41, secured thereon and formed with upwardly projecting loops at the centers of the covers forming vertically elongated eyes 43, receiving the 35 pivots 40. The covers are thus connected to their supporting arms by the pivots and elongated eyes, and each cover is allowed an independent vertical play so that when the cans are in normal position they will hold 40 the covers in elevated positions and hence carry and support the same, whereby the weight of the covers will hold them to 45 snugly fit and close the cans.

By employing this apparatus, the refuse 50 cans will be normally covered and closed and supported in an elevated position and not accessible to animals. The cans are attached to parts of the apparatus and hence will not be stolen and misplaced and are not so sub- 55 ject to damage and injury as where separate cans are employed that must be lifted and dumped. It will not be necessary for the 60 garbage and ash collection men to enter the premises nor in fact to disturb the occupants. The operator in the kitchen can 65 dump garbage and ashes into the carriage through a window or by stepping through the outside door, according to the arrangement of the particular apparatus, and can 70 discharge the contents of the carriage into

the storage cans without proceeding to said cans. The supporting devices for the cans can be arranged in the yard, beside the back or alley fence, so that the can to be dumped will swing above the fence and the can will 75 be carried over the wagon into the alley when the can supporting arm or bracket is extended.

It is evident that various changes, modifications, and variations might be resorted to 75 without departing from the spirit and scope of my invention and hence I do not wish to limit myself to the exact disclosures hereof.

What I claim is:—

1. In combination, means for supporting 80 an elevated storage can and for moving the same to and from receiving position and storage position and to and from storage position and discharging position, and an elevated carriage movable to and fro between a remote point and said receiving position, said carriage arranged to discharge its contents into said can when in said receiving position, and provided with supporting and operating means. 90

2. In combination, means for supporting 95 an elevated storage can and for moving the same to and from receiving position and storage position and to and from storage position and discharging position, and an elevated carriage movable to and fro between a remote point and said receiving position, said carriage arranged to discharge its contents into said can when in said receiving position, mechanism operative from 100 said remote point for propelling said carriage, and devices operative from said remote point for actuating said means supporting said storage can. 105

3. In combination, means for supporting 110 a storage can in elevated position, a carriage having a sliding bottom, said carriage adapted to move over said can and to discharge its contents thereinto, said bottom adapted to be moved to open position by 115 engagement with said can, means for propelling said carriage to and fro between a remote point and a discharge station at which station said carriage dumps its contents into said can, and devices for actuating said can supporting means to move the can back and forth between storage position and receiving position. 120

4. In combination, a carriage movable back 125 and forth between refuse receiving station and refuse discharging station, means operative approximately from said receiving station for propelling said carriage, a storage can, means for supporting said can and for moving the same to and fro between storage position and receiving position, said can receiving position being arranged under 130 said carriage discharge station, and devices for controlling the position of said can supporting means, said devices being operative

approximately from said carriage receiving station.

5. In combination, a support provided with a vertical rotatable pulley, another support at a remote point provided with a vertical rotatable actuating pulley, an endless traveling connection between and carried by said pulleys and propelled by said actuating pulley, a carriage propelled by said connection to and fro between said supports, a storage can supported in an elevated position by means comprising mechanism for moving said can to and from receiving, storing and dumping positions, said means carried by said first mentioned support, and devices whereby said carriage automatically discharges its contents into said can.

6. In combination, a support, a movable holder mounted thereon and carried thereby, a storage can mounted on said holder and held thereby in an elevated position to discharge its contents into a collection wagon, means for conveying refuse from a remote point and discharging the same into said storage can when said can is located in refuse receiving position, and devices operative from said remote point for moving said holder and for actuating said means.

7. In combination, an elevated support, a horizontally swingable elevated storage can holder mounted on said support, a storage can mounted on said holder, means for moving said holder to carry said can to and from storage position and refuse receiving position, and a cover for said can carried by said support and arranged to close the can when in storage position.

8. In combination, a support, a horizontally swingable cross head mounted thereon and at its opposite portions mounted with storage cans, means carried by said support for covering said cans when in normal storage position and means controlling the position of said cross head.

45 9. In combination, a support, means carried thereby for upholding several refuse cans in elevated position and for moving said cans from normal storage position to and from dumping and receiving positions, means whereby said cans can be dumped when in dumping position, and devices for delivering refuse to said cans when in receiving position.

10. In combination, a support, a horizontally swingable oppositely extending can holder mounted on said support and at its opposite portions provided with pivotally mounted dumping storage cans, and with means for normally holding said cans in upright position, and devices for controlling the position of said holder.

11. In combination, a support, a horizontally swingable storage can holder provided with a storage can, said holder being movable to carry said can to and from normal

storage position and receiving position, and to and from said storage position and can emptying position, means operative from a remote point for controlling the position of said holder, means operative from said remote point for delivering refuse into said can when said can is located at said receiving position, and means for covering said can when said can is located at storage position.

12. In combination, a support, a horizontally swingable storage can holder provided with a reversible dumping storage can and with means for normally maintaining said can in upright position, said holder being movable to carry said can to and from normal storage position and receiving position, and to and from said storage position and can emptying position, means operative from a remote point for controlling the position of said holder, and means operative from said remote point for delivering refuse into said can when said can is located at said receiving position.

13. In combination, a post, a horizontally turnable actuating member mounted on said post, a support at a remote point, a horizontally swingable holder mounted on said support and provided with and carrying storage cans movable by said holder to and from storage position, connections from said member to said holder for swinging said holder, and means for locking said member in various positions and thereby maintaining said holder in certain positions.

14. In combination, a support, a horizontally swingable holder mounted thereon, storage cans carried by said holder, a horizontally turnable member mounted on said support and adapted to swing said holder, a support at a remote point with respect to said first mentioned support and provided with a horizontally turnable actuating member, parallel flexible connections joining said turnable members to swing said holder, a carriage mounted on and movable longitudinally of said connections for conveying refuse to and discharging the same into said cans, and an endless propelling connection for said carriage provided with actuating means at said remote point.

15. In combination, a support, a can holder carried thereby in an elevated position, a can pivotally mounted on said holder, means whereby said can can be held in normal upright position and can be released to swing to dumping position and means for delivering and discharging refuse from a remote point to and in said can.

16. In combination, a support, a horizontal swingable oppositely extending can holder at its opposite portion provided with dumping storage cans with means for normally holding said cans in upright position, said holder comprising an extensible swing-

ing can carrying arm and means whereby refuse may be bodily transported from a distance away to said dumping storage cans.

17. In apparatus for the purpose substantially as described, a storage can holder provided with a storage can, said holder being movable to carry said can to and from normal upright storage position, a support, a pivotally mounted and vertically movable cover for said can, said cover being carried by said support independently of said

can and adapted to rest on and close said can when said can is in storage position and means operative from a distance away whereby refuse can be carried to and discharged in said storage can. 15

In testimony whereof I affix my signature in presence of two witnesses.

SAMUEL EDWARD JENKINS.
